UNITED STATES PATENT OFFICE

1,960,341

CEMENTING MACHINE

Irving L. Keith, Haverhill, Mass.

Application October 8, 1932, Serial No. 636,840

14 Claims. (Cl. 91—47)

This invention relates to cementing machines of the vertically movable, horizontally disposed grid type such as are shown in my Patent No. 1,311,605, dated July 29th, 1919 and that to McMurray #1,293,147 dated February 4th, 1919, and which are adapted to apply cement to sheet material laid therein.

In the manufacture of shoes, it is customary to cement together various parts thereof and in many instances it is desirable that certain portions of such parts, and frequently portions adjacent the edges thereof, be heavily coated with cement and that other portions be more lightly coated. Also in some instances it is desirous to have the cement applied only at the edge portion and some times in stripes across the surface. So far as I am aware the only method by which the edge portions only of such parts have been heavily coated with cement has been

20 by means of a hand brush, as the provision of mechanical means for applying cement in this manner to the edge portions of pieces of sheet material of various shapes and sizes has not been considered practical, if possible, and where it has been desired to coat one portion of a part heavily and another portion more lightly, it has been necessary to provide a specially constructed grid for the purpose, if the brush method was not to be employed.

25 The objects of my invention are to provide a cementing device, preferably of the grid type above referred to, which may be readily adapted to apply a continuous coating of cement to certain portions, or to the edge-portion only of cut-

30 out pieces of sheet material of various shapes and sizes, and at the same time to apply either a relatively small amount of cement, or practically no cement at all, to the other portions of the piece, or to coat some portions of a piece heavily and other portions lightly, so that the employment of the brush method, above referred to, may be dispensed with, or the provision of specially constructed grids may be made unnecessary, and these operations may be facilitated.

35 I accomplish these objects primarily by providing, in connection with cementing grids of the type above referred to, which have openings, a supplemental cement applying means, preferably in the form of a strip of resilient, flexible rubber, which is insertable in the openings of the grid, and, when the grid has vertically ex-

40 tending, spaced cementing projections, in the spaces between said projections, and which is

adapted to be held therein by frictional engagement therewith whereby the strip, or different sections thereof, which, as it is inserted in the grid openings or recesses, may be termed a filler, may be made to conform to an edge portion of a piece of sheet material, which is to be heavily cemented, thereby to provide a supplemental face for applying cement to such edge portion, or to any other portion of a piece of sheet material which is to be heavily coated with cement.

45 For a more complete disclosure of my invention, reference is now made to the following specification, in connection with the accompanying drawings in which:—

Fig. 1 is a plan view of a form of cementing grid provided with an embodiment of my invention.

Fig. 2 is a sectional view thereof at line 2—2 of Fig. 1.

Fig. 3 is a detail view in perspective of a portion 70 of the grid.

Fig. 4 is a detail sectional view of a modified form of the invention.

Fig. 5 is a view illustrating the work which may be performed by means of a grid of the form 75 shown in Fig. 1.

Fig. 6 is a plan view of another form of cementing grid provided with another embodiment of the invention.

Fig. 7 is a detail sectional view of a portion 80 of the grid.

Fig. 8 is a view of a shoe sole to which cement has been applied by the arrangement shown in Fig. 6.

Fig. 9 is a view of a cementing machine 85 of the type shown in said patent to McMurray.

As shown in the drawings, a cementing machine 90 of the type shown in said patent to McMurray is illustrated, said machine comprising a grid which

is composed of a series of flat bars *a* arranged in parallelism, each bar having a series of vertically disposed fingers, or projections *b* formed

therein, and said bars being spaced apart for a distance approximately corresponding to the distance between adjacent fingers thereon, so that

the cement applying faces on the top ends of the fingers are equally spaced, both longitudinally

and transversely of the grid, said faces being disposed in the same horizontal plane. It will be

understood that the grid is constantly supported in a horizontal position and is moved vertically

105 from a lowered position in which it is entirely submerged in the liquid cement contained in a

receptacle *c* directly beneath it, and a raised position in which it is supported above the level of

110 the cement, so that the sheet material to be cemented may be laid on the cement applying

100
105
110

faces of the fingers, thereby to transfer the cement thereon to the material.

According to one form of my invention, I provide a strip *d* of flexible material, preferably of resilient rubber, which is of a uniform width slightly greater than the distance between adjacent fingers, so that it may be close-fitted or forced therebetween in directions either transversely or longitudinally of the grid. Said strip is also of a thickness corresponding to the length of the fingers, so that, when inserted between adjacent fingers on a bar, it will rest on the edges of the bar and be supported thereby. In practice the strip is bent to conform to the pattern of a particular piece of sheet material, the edge portion of which is to be heavily cemented, and the strip is pressed down between the fingers in this form, so that its top surface is flush with the top faces of the fingers, as shown in Figs. 1, 2 and 3. The strip will thus be held in position to conform to the pattern of a particular piece of material to be cemented, the particular pattern shown in Fig. 1 being merely illustrative.

In using the above described device, after the flexible filler strip has been inserted in a formation corresponding to the pattern of the piece of sheet material to be cemented, the grid is submerged in the cement and raised in the usual manner, and then the piece of material is laid on the grid with its edge approximately in coincidence with the outer edge of the strip *d*. As the top surface of the strip will be coated with cement, the cement thereon will, to a large extent, be transferred to the edge portion of the piece, so that its edge portion will receive a solid coating of cement and its inner portion will have the cement applied thereto in dots, as indicated in Fig. 5, the operation on the inner portion of the piece being identical to that performed by the McMurray grid.

In some instances it is not necessary to apply the cement to the inner portion of the piece, in which instance a strip will be employed which is of slightly greater thickness than the depth of the recesses in the bars between the teeth, so that the top surface of the strip will be supported at a short distance above the top ends of the fingers, as shown by the strip *d'* in Fig. 4, so that, when the material to be cemented is laid onto the strip, as before described, the strip will hold the piece out of contact with the ends of the fingers, and cement will only be applied to the edge portion of the material, except where its inner portion may come in contact with the fingers by accident.

In Figs. 6 and 7 a form of grid is illustrated similar to that shown in my said Patent No. 1,311,605, in which a series of flat bars *e* are held in parallel relation and are spaced uniformly to provide openings therebetween, the upper edges of the bars being disposed in the same horizontal plane and providing cementing faces, so that normally the grid will apply the cement in stripes to the material laid thereon. As with this form of grid the filler cannot be extended across the bars. I provide a series of resilient sections, or blocks *f*, which are preferably composed of resilient rubber and are of slightly greater width than the width of the openings between the bars, so that said sections may be forced into the openings by slightly compressing them and will be held in the position in which they are placed by frictional engagement. The sections may be made square in cross section as shown by the sections *f*, or elongated, as shown by the sections *g*. As

shown in Fig. 6, the square sections may be arranged to correspond to the outline of a shoe sole, when it is desired to apply a heavy coating of cement to its edge portion, and if, in addition, it may be desired also to apply the cement to certain portions thereof in heavy transverse stripes, the elongated section *g* may be forced into the openings between the bars in the positions desired, so that the sole may have cement applied thereto in the manner indicated in Fig. 8.

The sections *f* or *g* may obviously be employed in connection with a grid of the type shown in Fig. 1, or they may be employed therein in connection with the elongated flexible strip *d*.

By employing a filling device of the above described character, and, in the manner indicated, in connection with practically any form of grid of the general type shown, the grid may be adapted to apply a heavy coating of cement to the edge portion of pieces of sheet material of various shapes, or to certain portions only of such pieces, and the necessary changes in location of the filler may be quickly made by the operator. The operation of applying a heavy coating of cement to some portions and a light coating to other portions may be performed as rapidly as if the cement were applied uniformly throughout the entire surface, thereby making the use of a brush unnecessary and enabling a single machine to be employed for a wide range of work.

I claim:

1. A cementing grid of the type described having a cementing face and openings therethrough, a filler removably insertable in said openings to provide a supplemental cementing face.

2. In combination with a cementing grid of

the type described having openings therethrough

and cementing faces adjacent said openings, a

filler removably insertable in different positions

in said openings to provide a supplemental ce-

menting face in different locations with relation

to the faces of the grid.

3. In combination with a cementing grid hav-

ing transversely extending openings there-

through, cementing faces adjacent said openings

and recesses in its top side connecting said open-

ings, filling material removably insertable in said

openings and recesses to provide a supplemental

cementing face of variable formation.

4. In combination with a cementing grid hav-

ing elongated openings therethrough, and ce-

menting faces adjacent said openings, a strip of

material removably insertable in said openings

to provide an elongated supplemental cementing

face in different positions on the grid.

5. In combination with a cementing grid having

upwardly extending cement applying projections

arranged over its surface in spaced relation, a

filling material removably insertable between

said projections and arranged to provide a rela-

tively narrow supplemental cement applying face

of variable formation.

6. In combination with a cementing grid hav-

ing upwardly projecting fingers arranged there-

on in spaced relation and having cement apply-

ing faces on their upper ends, filling material

removably insertable between said fingers and

arranged to provide a cement applying face be-

tween the faces of said fingers at the level of

said faces.

7. In combination with a cementing grid hav-

ing openings therethrough and cementing faces

adjacent said openings, a filler of resilient ma-

terial adapted to be forced into said openings

and to be retained therein by its frictional en-

gagement with the sides thereof, to provide a supplemental cementing face in different locations on the grid.

8. In combination with a cementing grid having openings therethrough and cementing faces adjacent said openings, a strip of flexible material insertable in different positions in said openings to provide an elongated supplemental cementing face.

10 9. In combination with a cementing grid having cement applying fingers projecting upwardly therefrom in spaced relation, a strip of flexible material insertable between said fingers, to provide an elongated supplemental cementing face adjacent the ends of said fingers of variable formation.

10 10. In combination with a cementing grid having fingers projecting upwardly therefrom in uniformly spaced relation, and having cement applying faces on their ends, a strip of flexible resilient material of a uniform width corresponding to the spaces between said fingers and inserted between the same in a formation corresponding to the contour of a piece of sheet material to be cemented, to provide a cementing face supplemental to the faces of said fingers.

20 11. In combination with a horizontally disposed cementing grid having uniformly spaced, upwardly projecting fingers provided with ce-

menting faces on their upper ends arranged at a uniform level, and a strip of flexible material of a width corresponding to the width of the spaces between said fingers and in which said strip is inserted in predetermined formation with its top side adjacent the level of said faces, and in position to provide a supplemental cementing face.

12. In combination with a horizontally disposed cementing grid having cementing faces disposed at a uniform level and having openings therebetween, a filler insertable in said openings and arranged with its top side adjacent and above the level of said faces, and in position to provide a supplemental cementing face.

13. In combination with a cementing grid having openings therethrough and cementing faces adjacent said openings, a series of separate filler sections insertable in said openings to provide supplemental cementing faces of variable formation.

14. In combination with a cementing grid having openings therethrough and cementing faces adjacent said openings, a series of separate filler sections of yieldable, resilient material adapted to be forced into said openings and to be held therein by frictional engagement, to provide supplemental cementing faces.
